UNITED STATES PATENT OFFICE.

JOSEPH J. CORY, OF ROCHESTER, NEW YORK.

NON-REFILLABLE BOTTLE.

1,275,856.

Specification of Letters Patent. Patented Aug. 13, 1918.

Application filed February 2, 1918. Serial No. 215,104.

To all whom it may concern:

Be it known that I, JOSEPH J. CORY, a citizen of the United States, residing at Rochester, in the county of Monroe and 5 State of New York, have invented new and useful Improvements in Non-Refillable Bottles, of which the following is a specification.

This invention relates to a bottle of the 10 non-refillable type and the primary object of the invention is to provide a receptacle of this character having a neck which comprises a unitary structure throughout its length and is provided with means whereby 15 a valve of novel construction adapted to control the passage of liquid through the bottle neck may be held out of engagement with the seat therefore during the initial filling of the bottle.

20 With these and other objects in view the invention resides in the novel combination and arrangement of parts which will be hereinafter described and particularly pointed out in the claims.

25 In the drawing—

Figure 1 is a view in side elevation partly in section of a bottle the neck of which is constructed in accordance with the invention.

30 Fig. 2 is a view similar to Fig. 1 with the bottle inverted.

Fig. 3 is a cross section on the line 3—3 of Fig. 1.

35 Fig. 4 is a detail perspective view of the valve.

Like characters of reference denote the corresponding parts throughout the several views in the drawing.

Referring now to the drawing in detail 40 the letter A designates a bottle wherein the neck B is constructed in accordance with the invention and comprises a unitary structure throughout its length.

The neck B of the bottle has formed there- 45 in at diametrically opposite points, open- ings 5 which are in line with an annular groove 6 in the inner wall of the bottle neck. A partition 7 extends transversely of the bottle neck above the groove 6 and is pro- 50 vided with a central opening 8 which estab- lishes communication between a pair of chambers 9 and 10 formed in the bottle neck by the partition 7. The chamber 10 is dis- posed below the partition 7 and gradually 55 decreases in diameter from its upper to its lower end, so that the wall of the chamber

may be employed in connection with the wall of the groove 6, to act as a seat for a valve 11 which is located in the chamber 10 and controls the passage of fluid through 60 the neck B.

The valve 11 comprises a substantially cone shaped stem 12 which is of greater length than the chamber 10 and is provided at its base with a circumferentially extending flange 13. Formed integral with the apex of the stem 12 is a disk 14 which when the bottle is inverted engages with projections 15 at the lower end of the neck and prevents the opening 8 from being closed by 70 the valve.

Arranged within the openings 5 in the neck B are pins 16 the inner ends of which are beveled as shown to correspond to the curvature of the wall of the groove 6. The 75 pins 16 are retained in the openings 5 by means of cement and are not only adapted to serve as closures for these openings but at the time the bottle was filled are adapted to have their beveled ends inserted beneath the 80 flange 13 to hold the valve 11 out of engagement with its seat and allow the contents of the bottle to be poured therein through the neck B. The opening 8 in the partition 7 is closed by a cork 17 which is 85 inserted in the chamber 9 and extends above the mouth of the neck B.

When it is desired to pour the contents from the bottle A the bottle is inverted as shown in Fig. 2 in the drawing which causes 90 the valve 11 to leave its seat and to be supported within the chamber 10 through the engagement of the disk 14 with the projections 15.

When the bottle is restored to its normal 95 position the valve 11 is caused by gravity to engage its seat and prevent any liquid which might be poured within the chamber 9 enter- 100ing the bottle body.

From the foregoing description taken in 100 connection with the accompanying drawings it is apparent that a non-refillable bottle has been provided wherein provision has been made for maintaining a valve which controls the passage of fluid through the bot- 105tle neck out of engagement with its seat dur- ing the initial filling of the bottle.

Having thus described the invention what is claimed as new, is:

1. A bottle having a valve in its neck 110 adapted to control the passage of fluid there- through and means comprising a part of the

bottle neck adapted to be engaged with said valve at the time the bottle was filled to support the valve in position in the bottle neck to allow liquid to pass through the neck into the bottle.

2. A bottle having a neck provided with openings therein, a valve in the bottle neck adapted to control the passage of liquid therethrough and pins in said openings adapted to be engaged with said valve at the time the bottle was filled to hold said valve in position in the bottle neck to allow liquid to be poured through the neck into the bottle.

15 3. A bottle having a neck provided with spaced openings therein, a valve in the bottle neck to control the passage of fluid therethrough having a circumferentially extending flange at one end thereof, pins closing

the openings in the bottle neck, and beveled ends on said pins adapted to be inserted beneath the flange on the valve to hold the same in position within the neck to allow fluid to be passed through the neck and into the bottle.

25 4. A bottle having an annular groove in the inner wall of its neck, a valve seat in the bottle neck below said groove, a valve in said neck engageable with said seat having a circumferentially extending flange thereon extending within said groove, pins in said neck in line with said groove, and beveled ends on said pins adapted to be passed beneath the flange on said valve to hold valve out of engagement with its seat during the 30 filling of the bottle.

In testimony whereof I affix my signature.
JOSEPH J. CORY.
